UNITED STATES PATENT OFFICE.

WILLIAM NICHTHAUSER, OF NEW YORK, N. Y.; MAUD S. NICHTHAUSER, EXECUTRIX
OF SAID WILLIAM NICHTHAUSER, DECEASED, ASSIGNOR TO NICHTHAUSER & LEVY,
A CORPORATION OF NEW YORK.

SIFTER.

1,137,886.

Specification of Letters Patent.

Patented May 4, 1915.

Application filed May 24, 1912. Serial No. 699,455.

To all whom it may concern:

Be it known that I, WILLIAM NICHTHAUSER, a citizen of the United States, residing at borough of Manhattan, in the county of New York and State of New York, have invented certain new and useful Improvements in Sifters, of which the following is a specification, reference being had therein to the accompanying drawings, 10 forming part thereof.

My invention relates to sifters and particularly coal and ash sifters and has for its objects simplicity and economy of manufacture, strength and durability of construction, efficiency, reliability and neatness of operation.

My invention also has for its objects to provide for the adjustment and adaptability of the sifter to fit material receiving receptacles of various sizes and to confine and retain the dust and ashes so as to insure a comparatively dust proof apparatus.

My invention also has for its object to provide for the unobstructed and uninterrupted movement of the material dumped into the feed chute into and through the sieve without any clogging of the material therein.

My invention also has for its object to provide a sieve of simple and durable construction and with strengthening members along its side and ends to impart the necessary rigidity.

My invention has other objects which will 35 appear more fully hereinafter.

My invention includes a cylindrical sieve arranged to rotate on an inclined shaft and secured to said shaft by cross strips so positioned that no clogging up of the outlet for 40 the feed chute or retardation of the material passing through the sieve will result therefrom.

My invention also includes means for joining together the edges of the sheet forming the cylindrical sieve of my invention, said means consisting of selvage strips provided with coöperating hook-like portions adapted to be held in locking engagement with one another and thereby making unnecessary the soldering together of the two 50 separate parts.

My invention also includes adjustable

means whereby the sifter may be mounted on barrels, cans and like material receiving receptacles of different sizes, and so located 55 or positioned thereon that the opening at the base of the casing will be at all times in coöperative relation with the open end of the material receiving receptacle.

My invention includes other features and details of construction which will appear more fully hereinafter.

I shall now describe my invention as illustrated in the accompanying drawings and shall thereafter point out my invention in 65 claim.

Figure 1 is a side elevation in section of one embodiment of my invention. Fig. 2 is a bottom view of the same with the feed and outlet chutes removed. Fig. 3 is a side elevation of the revoluble sieve. Fig. 4 is an end view of the same. Fig. 5 is an enlarged plan view of the joint connecting the edges of the sheet forming the sieve. Fig. 6 is an enlarged sectional end view of the same. 75

In the specific embodiment of my invention which I have illustrated in the accompanying drawings, a hollow cylindrical sieve is shown mounted upon a shaft 2 fitted in bearings 3 and 4 to rotate therein. This 80 shaft is shown as somewhat inclined toward the rear of the apparatus so as to give a downward slope to the sieve and thereby facilitate the passage of the material along its length. An extended portion is provided 85 at its forward end and bent to form a handle 5.

The sieve is inclosed on the top and sides thereof within a casing 6, the upper portion of the casing being arched and inclined longitudinally to conform with the curved and inclined outline of the sieve 1. At the forward part of the casing 6 and riveted thereto is shown a feed chute 7 having sloping sides and bottom upon which the material is 90 dumped and guided directly into the sieve 1. An extending guide plate 9 is riveted or otherwise secured to the inclined base 7a of the chute 7 and is adapted to lead the material directly into the adjacent, open end of 100 the sieve 1.

In the specific embodiment of my invention herein illustrated, the sieve 1 consists of a sheet of wire woven to form a mesh of

small squares or perforations through which the material is sifted. This sheet is rolled or otherwise shaped to form a hollow cylinder, the edges of which are connected together by selvage strips or bands 10 and 11. These strips are shown as made in the form of an italicized *y*, the portions 10^a and 11^a thereof being adapted to receive and hold the edges of the sheet and the hook shaped portions 10^b and 11^b of the strips being adapted to be hooked one with the other and held thus in locked engagement. The flaps are adapted to be pressed or otherwise forced together to hold firmly the parts held therein, making unnecessary the use of soldering tools and solder so common in work of this character. These strips when so locked and bound together serve as a stiffening or strengthening band extending the length of the sieve.

The sieve 1 is shown as further strengthened by strengthening hoops or rings at each end of the strips 10-11 and of the sieve 1. These hoops 12 and 13 are shown as made from folded V-shaped selvage strips in the open portions of which the edges of the sheet 1^a are inserted and held.

Connections between the perforated sheet 1^a forming the sieve and the rotating shaft 2 are made at each end of the cylinder by flat strips 14 and 15 shown as extending from the hoops 10 and 11 respectively, and radially across the cylinder to the shaft 2. The forward strip 14 is shown as secured at one end to the hoop 12 and as extending rearwardly and along the inner surface of the cylinder for a substantial distance and thence downwardly and across the open end of the cylinder to the shaft 2 to which it is held by the bearing plate 16. That portion 14^a of the strip 14 extending radially and across the cylinder is bent or turned so that its wider faces are in planes parallel to the longitudinal axis of the shaft 2 and with the bearing plate 16 provides a long bearing in which the shaft is firmly held. This construction permits the entrance of the guide plate 9 into the open end of the cylinder 1 for a substantial distance and insures the proper feeding of the material therein during the rotation of the sieve. The bending of the strip 14 with its wider faces in alignment with the shaft 2 offers the least obstruction to the entrance and passage of the material through the sieve.

The rear strip 15 is shown as secured to the rear hoop 11 and extending radially and across the rear opening of the cylinder 1 and to the shaft 2 to which it is firmly secured by a bearing plate 16. As in the case of the strip 14, it is bent or turned so that its wider faces are in alignment with the shaft 2 so as to offer the least obstruction to the passage of the coal or cinders or the like out of the

cylinder and through the outlet chute 18 and 65 into the receptacle suspended from the hook 17. This hook is shown as riveted or otherwise secured to the rear wall 23 of the casing 6 and provides along its upper portion the rear bearing 4 of the shaft 2. The front 70 bearing 3 is shown as provided by a V shaped plate 24 riveted or otherwise secured on the front face of the feed chute 7.

The base portion of the apparatus is provided with an opening 19 through which the 75 sifted material falls into the barrel, can or like receiving receptacle 20 positioned beneath. The base portion is shown as provided with a depending flange or rim 21 adapted to fit over the receptacle 20. Plates 80 22 are shown mounted on the under face of the base 25 and diametrically opposite each other and having depending portions 22^a arcuated or curved to conform to the curve of the opening 19 and positioned so as to 85 enter within the walls of the receiving receptacle 20. There is further shown adjusting means 26 for shifting or otherwise adjusting the plates 22 on the base 25 to vary the position of the depending portions 90 22^a relative to the walls of the receiving receptacle 20. This construction permits of the use of receiving receptacles of different sizes in connection with the sifter since the depending portions 22^a serve to hold the base 95 portion within certain limits with respect to the opening in the receiving receptacle and thus insures the falling of the sifted material therein.

Throughout the structure of the apparatus embodying my invention the joints are so constructed as to insure a dust proof apparatus. The arched casing 6 is provided along its front end with an inclosing wall 27 which is secured thereto and to which in turn the rear vertical wall 7^b of the chute and the inclined base 7^a are riveted. Where the chute 7 is joined to the front wall 27 and the latter in turn is secured to the base portion 25, the joints are so constructed that 110 lodgment of dust and ashes therein is made almost impossible.

It is obvious that various modifications may be made in the construction shown and above described within the spirit and scope 115 of my invention.

I claim:

In a sifter, a cylindrical sieve comprising a perforated sheet shaped to form a hollow cylinder open at each end, strengthening 120 hoops secured at each end thereof, a shaft extending through said cylinder, and a flat radial strip extending diametrically across the forward end of said cylinder and then bent and made to lie flat against the inner 125 walls of said cylinder and connecting the forward hoop with the shaft and firmly securing them together so that the rotation of

the shaft will rotate the cylinder, the portion of said radial strip which extends across said cylinder being turned with its wider faces parallel to the longitudinal axis of the cylinder so as to provide the least obstruction to the entrance and passage of material rearwardly and through said cylinder, and being further bent at its medial portion

to provide a seat in which the rotating shaft is removably secured.

In testimony whereof I have affixed my signature in the presence of two witnesses.

WILLIAM NICHTHAUSER.
